UNITED STATES PATENT OFFICE.

HERMAN J. HAMMERLY, OF WALLINGFORD, CONNECTICUT, ASSIGNOR TO THE TRUMBULL ELECTRIC MANUFACTURING COMPANY, OF PLAINVILLE, CONNECTICUT, A CORPORATION OF CONNECTICUT.

INCLOSED SWITCH CONSTRUCTION.

Application filed October 8, 1928. Serial No. 311,067.

My invention relates to the class of inclosed switches which are mounted in a box having a cover which may be locked or sealed closed to prevent unauthorized access 5 to the switch per se or its terminals and an auxiliary interlocking shutter door carried by the cover, which door may be readily opened by the current consumer to permit manipulation of the fuses when the switch 10 is positively locked in the off position but which door is automatically locked against opening movement while the switch is in the on position.

I am aware that a number of patents have 15 been issued on switch constructions in which the above enumerated safety features have been incorporated in a more or less practical manner but many of the constructions shown are open to objections from the commercial or practical standpoint.

My present invention obviates many of the objections which are obvious in a showing of the prior art.

One object of my invention is to provide 25 an inclosed safety switch construction including a satisfactory sliding shutter fuse door as distinguished from a hinged or pivoted fuse door or the equivalent.

Another object is to provide a safety 30 switch construction with a sliding shutter fuse door together with an interlocking bar which projects outside of the box in such a manner as to indicate clearly whether or not the fuse door is interlocked as well as 35 where and just how it is interlocked with the operating handle.

Another object is to provide an interlocking fuse door construction in which none of the co-related parts are hinged or pivoted.

Another object is to provide an interlocking fuse door construction in which all small 40 parts such as latches, connecting levers, springs, rivets, etc. are entirely eliminated and the interlocking functions are accomplished positively and solely by the interengagement of the major elements in the 45 normal operation of the switch.

Another object is to provide a safety switch construction having a sliding shutter 50 fuse door so co-related with the operating

handle that the fuse door cannot be opened while the switch is closed, so that the switch cannot be closed while the fuse door is open and so that the main switch cover can be opened whether the switch is open or closed. 55

Some of the commercial requirements in a construction of this character are that it be comparatively cheap as well as sturdy and practical; these requirements are met by the construction herein disclosed. 60

The drawings show the preferred form of construction embodying my invention.

Fig. 1 is a perspective view of an inclosed switch showing the slide open to permit replacement of the fuses and showing the interlock holding the operating handle in the open circuit position. 65

Fig. 2 is a transverse horizontal section of the construction with the slide closed.

Fig. 3 is a front view showing the box open. 70

Fig. 4 is a detailed view of parts of the cover and slide and interlocking members.

The box 6 has a cover 7 which may be 75 hinged to it in the usual manner and which may be provided with a spring catch 8 whereby the cover may be latched or locked in the closed position.

The switch construction may be of any 80 suitable type. The insulating base 10 is supported by brackets 11 and carries stationary contact jaws 12. The removable switch blades 13 are carried by an insulating cross bar 14 which is supported by connected rods 15 85 which extend through the base. The operating crank 16 is pivotally supported in the box and engages the connector rods 15 and is provided with an external operating handle 17 adapted to rotate and swing along the side 90 of one wall of the box. The strap or bracket 18 serves as a guard for the handle and also as a means for locking or sealing the handle in either the open or closed circuit position.

The fuses 20 are detachably mounted in 95 any suitable manner within a receptacle 21 having side walls, the outer edges of which extend close to the inner surface of the cover.

The cover is provided with an opening 22 100

through which access may be had to the fuse chamber.

A slide 23, supported in guideways 24 attached to the inside of the cover, normally covers the opening 22. The handle 24' serves as a means for operating the slide as well as a stop to limit the movement of the slide. The interlocking member 25 is preferably formed of heavy wire or rod and 10 has two arms or branches 26 and 27 which are guided in suitable openings in the flange 28 of the cover. The longer arm 27 is also guided in an opening in a bracket or flange 29 secured to the cover near one of the guide- 15 ways. To the inner face of the slide 23 is secured a grooved or channel-like guide member 30 secured, for instance, by welding or riveting. The inner end of the interlocker rod 27 is bent over at an abrupt angle to 20 form a projection 31 adapted to slide in the channel member 30. Obviously the interlocking member 25 may be made of sheet or cast metal if so desired.

Obviously, the angular relation of the interlocker member 25, the slide 23 and the guide channel 30 together with the relatively straight movement of the slide, will cause a transverse movement of the interlocker member 25 when the slide is moved up or down 25 so that when the switch box is closed and the switch is in the closed circuit position, the handle 17 stands directly in the path of movement of the projecting outer end of the interlocking member 25. When the switch 30 is open, however, and the handle in the position shown in Fig. 1, the slide 23 may be moved downwardly to the position shown. The engagement of the inclined channel 30 with the inner end 31 of the interlock 25, 35 causes the interlock to move outwardly into the path of movement of the handle 17 as shown in Fig. 1, so that the switch can not be operated when the fuse compartment is open. It will be understood of course that when the 40 cover is open, the switch may be operated without any interference of the interlock.

The parts are all simple and so proportioned and arranged as to provide a maximum strength and solidity with a minimum weight of material.

The handle engaging portion of the interlock bar 25 is exposed at all times so that its relation to the handle is apparent at a glance. 55 There is therefore no damage due to the operator unwittingly straining or injuring the parts in a legitimate attempt to operate the switch when the slide is open or to operate the slide when the switch is closed.

60 The angular relation of the interlocking parts is such that the slide 23 will stay open or closed or in an intermediate position without the use of springs, catches or friction devices.

65 It will be apparent from the foregoing

that the objects of this invention have been accomplished in a very practical manner with a minimum number of single parts and that the construction is of a very rugged and substantial character.

70

I claim:

1. A safety switch including a box having a cover, a movable switch member mounted in said box and having an operating handle outside of said box, said cover having an opening, a slide for closing said opening, a wire handle obstructing stop guided inside of the cover in line with the handle and an inclined guide connected to said slide and having operable engagement with said stop to move said stop in a transverse direction when said slide is moved.

75

2. A safety switch including a box having a flanged cover hinged thereto, a movable switch member mounted in said box and having an operating handle extending outside of said box, said cover having an opening, a slide for closing said opening, a wire loop handle stop guided in one flange of the cover in line with the handle and an inclined guide 85 carried by the slide and having operable engagement with said stop to move said stop in a transverse direction when said slide is moved.

80

3. A safety switch including a box having a flanged cover with an opening, a slide for said opening, a switch mounted in the box and having an external operating handle and a handle latching rod supported to slide in a flange of the cover and having one end slidably connected with said slide and the other end adapted to coact with said handle, at the 90 edge of the cover when the cover is closed.

95

4. A safety switch including a box having a cover hinged thereto, a switch mounted in said box and having a swinging operating handle outside of said box, said cover having an opening, a slide for closing said opening, a handle stop guided in the cover in line with the handle, an inclined guide connected to said slide and having operable engagement with said stop to actuate said stop, and a strap secured to said box and extending around said handle adjacent the outer end of the stop rod.
